UNITED STATES PATENT OFFICE.

JOHN E. BELL, OF BARBERTON, OHIO, ASSIGNOR TO THE BABCOCK & WILCOX COMPANY, OF NEW YORK, N. Y., A CORPORATION OF NEW JERSEY.

SUPERHEATER-BOILER.

No. 857,014.

Specification of Letters Patent.

Patented June 18, 1907.

Application filed April 4, 1905. Serial No. 253,833.

To all whom it may concern:

Be it known that I, JOHN E. BELL, of Barberton, Summit county, Ohio, have invented a new and useful Superheater-Boiler, of which the following is a full, clear, and exact description, reference being had to the accompanying drawings, forming part of this specification, in which--

Figure 1 is a diagrammatic cross-section of a superheater boiler constructed in accordance with my invention; Fig. 2 is a sectional side elevation of the same; Figs. 3 and 4 are views similar to Figs. 1 and 2, showing a modified form; Figs. 5 and 6 are views similar to Figs. 1 and 2, showing another form; Fig. 7 is a view similar to Fig. 6 showing a modification of the form of Fig. 5; and Figs. 8 and 9 are views similar to Figs. 1 and 2 respectively, showing another arrangement of furnace and baffles.

My invention relates to the class of water tube boilers having longitudinal upper and lower drums, the gases passing longitudinally of the drums.

The invention is designed to combine a superheater with such a type of boiler in an efficient and economical manner.

In the drawings, referring to the form of Figs. 1 and 2, 2 represents a longitudinal steam and water drum, and 3 a longitudinal parallel mud drum, 4 is the front wall and 5 the rear wall of the setting, 6 the offtake and 7 the furnace, 8 is the roof or arch of the combustion chamber which extends rearwardly a portion of the length of the mud drum, and is provided with a narrow baffle extension 9 beneath the remaining portion of the mud drum, leaving ports 10, 10 opening upwardly on each side of the drum 3 at its rear.

11 is a baffle which extends upwardly between the water tubes 12 which connect the steam and water drum with the mud drum, and 13 is a depending baffle in front of the water tubes.

In line with the baffle 13 the steam and water drum is provided with a transverse partition 14 having a connecting hole or opening 15 in its upper portion, while the mud drum has a corresponding separating partition 16. In the front of these partitions, the two drums are connected by superheater tubes 17. These tubes are divided into

two sets by a separating partition 18 in the upper drum.

In the use of the apparatus the flame and gases rise around the rear part of the mud drum, flow up among the tubes 12 to the top of the baffle 11, thence down among the other water tubes to the lower end of the baffle 13, and thence up among the superheating tubes to the offtake 6. The steam generated in the steam and water drum flows through the hole 15 into the steam compartment, and thence down through one set of superheating tubes 65 and up through the other set of superheating tubes into the outer steam compartment where it is taken off through outlet 19.

In Figs. 3 and 4 I show a similar apparatus except that two steam and water drums 2^a are provided, each connected by the tubes 12^a to the single mud drum 3^a. Each of the upper drums is provided with partitions as shown in Figs. 1 and 2, similar parts being indicated by similar numerals 75 with the letter *a* applied.

In Figs. 5 and 6 I show a form similar to Fig. 1, except that three steam and water drums 2^b are provided connected by the tubes 12^b to the single mud drum 3^b.

In Fig. 7 I show a form similar to that of Fig. 5, except that the superheater tubes 17^b are located in the middle pass of the gases. In this case in addition to the apertured partitions 14^b of the upper drum, they are provided with the partition 18^b and a third separating partition 20. The partition 20 is connected to the partition 18 by an upper tube 21 so that the steam generated in the front water compartment may pass to the compartment between the partitions 14^b and 18^b. The lower drum is provided with a second partition 22 and water tubes extend between the partitions 16^b and 22 and between the lower parts of the partitions 14^b and 20 of the steam and water drum.

In the form of Figs. 8 and 9 the furnace 7^d is exterior to the setting at one end. The flame and gases from the furnace pass in among the tubes 12^d and are given three up and down passes the same as in Figs. 1 and 2. The partition of the drums and the general arrangement is the same as that of Figs. 1 and 2, similar parts being designated by similar numerals with the letter *d* applied.

The advantages of my invention result

from combining a superheater with a water tube boiler having upper and lower longitudinal drums, the gases passing longitudinally of the drums. The baffles which are 5 preferably used give the gases up and down passes, and the first pass is preferably entirely occupied by water tubes to prevent injury to the superheating tubes. An efficient and economical apparatus is thus provided in 10 which the steam is produced and superheated in the same setting.

The superheaters may be provided with 15 return-bend or U-shaped tubes, the arrangement of the drums may be varied, and many 15 other changes may be made without departing from my invention.

I claim:—

1. A water tube boiler having upper and lower longitudinal drums connected by water 20 tubes, means for passing gases longitudinally of the drums, and a superheater in the boiler structure and connected to the steam space of the boiler, said boiler having water-heating tubes between the source of heat and the 25 superheater, substantially as described.

2. A water tube boiler having upper and lower longitudinal drums connected by water tubes, baffles arranged to give the gases up and down passes among the tubes longitudinally of the drums, and a superheater located in the boiler setting, said superheater being exposed to the heat of the gases and connected to the steam space of the boiler, said boiler having water-heating tubes 35 between the source of heat and the superheater; substantially as described.

3. A water tube boiler having longitudinal upper and lower drums connected by water tubes, baffles arranged to give the gases 40 serial up and down passes longitudinally of the drums and among the water tubes, and a superheater forming at least the major portion of the heating surface in a pass back of the first pass of the gases among the tubes; substantially as described.

4. A water tube boiler having a single mud drum connected by water tubes to an upper steam and water drum or drums, said drums extending longitudinally, baffles arranged to 50 give the gases up and down passes, longitudinally of the mud drum, and a superheater forming at least a major portion of the heating surface in a pass in the rear of the first pass of the gases; substantially as described.

5. A boiler having longitudinal upper and lower drums connected by water tubes, a part of each of the drums being cut off by a transverse partition forming steam chambers, superheating tubes connecting said chambers and means for passing heated gases over the tubes and longitudinally of the drums; substantially as described.

6. A water tube boiler having an upper 65 steam and water drum divided into water

and steam chambers, the water chamber being located between the steam chamber and the source of heat, upright water tubes in the path of the heat and connected with the water chamber, and upright superheating tubes in rear of the water tubes with respect to the path of heat and connected to the steam chamber.

7. A water tube boiler having longitudinal upper and lower drums connected by water tubes, baffles arranged to give the gases up and down passes longitudinally of the drums among the tubes, the upper drum having a cross partition forming a steam chamber, and superheating tubes connected 70 to said steam chamber and forming at least a major part of the heating surface in one pass of the gases; substantially as described.

8. A water tube boiler having an upper steam and water drum divided by transverse partitions into a water chamber and steam chambers, the water chamber being located between the source of heat and the steam chambers, and upright superheating tubes connected to the steam chambers and disposed to produce at least two up and down passes to the steam.

9. A water tube boiler having upper and lower drums provided with transverse partitions dividing the drums into water and steam chambers, the water chambers being located between the source of heat and the steam chambers, and upright superheating tubes connecting the steam chambers of the drums and disposed to give at least two 100 up and down passes to the steam in the superheating tubes.

10. A water tube boiler having a plurality of longitudinal steam and water drums connected by water tubes to a longitudinal mud drum or drums, a baffle extending transversely of the drums, and a superheater in the boiler setting located back of the first pass of the gases; substantially as described.

11. A water tube boiler having upper and lower longitudinal drums connected by water tubes, a chamber below the mud drum or drums with ports leading upwardly among the tubes at one end, a baffle arranged to give up and down passes to the 115 gases longitudinally of the drums, and a superheater located in a pass in the rear of the first pass; substantially as described.

12. A water tube boiler having longitudinal upper and lower drums connected by water tubes, baffles arranged to give at least three up and down passes to the gases longitudinally of the drums, and a superheater forming at least the major part of the heating surface in one pass in the rear of the first 125 pass; substantially as described.

13. A water tube boiler having a plurality of longitudinal steam and water drums, connected by water tubes to a longitudinal mud drum or drums, an inlet for heating gases at 130

- one end, baffles arranged to give the gases at least three up and down passes, and a superheater forming at least the major part of the heating surface in a pass of the gases in the rear of the first pass; substantially as described.
14. A water tube boiler having a plurality of upper longitudinal steam and water drums connected by water tubes to a mud drum or drums, cross partitions in the upper drums forming steam chambers, and superheating tubes connected to said chambers, said boiler having water-heating surface between the source of heat and the superheating tubes; substantially as described.
15. A water tube boiler having a plurality of upper longitudinal steam and water drums connected by water tubes to a mud drum or drums means for passing gases up and down the tubes longitudinally of the drums, cross partitions in the upper drums forming steam chambers, and superheating tubes connected to said chambers and forming a major part of the heating surface in a pass of the gases in the rear of the first pass; substantially as described.
16. A water tube boiler having upper and lower longitudinal drums connected by water tubes, means for passing the gases longitudinally of the drums and up and down over the water tubes, and a superheater located in the boiler structure and having upper and lower chambers or drums connected by steam tubes, said superheater forming the major portion of the heating surface in a pass back of the first pass of the gases; substantially as described.
17. A water tube boiler having upper and lower longitudinal drums connected by water tubes, means for passing the gases longitudinally of the drums and over the water tubes, and a superheater located in the boiler structure and having upper and lower chambers or drums connected by steam tubes, the boiler having water tubes between the superheater and the source of heat; substantially as described.
18. A boiler having a single mud drum connected by water tubes to an upper steam and water drum or drums, said drums extending longitudinally of the setting, a furnace below the mud drum with ports leading upwardly to the tubes at one end, a baffle arranged to give up and down passes to the gases longitudinally of the drums, and a superheater in rear of the first pass and having one or more chambers or drums provided with superheating tubes, substantially as described.

In testimony whereof, I have hereunto set my hand.

JOHN E. BELL.
